UNITED STATES PATENT OFFICE.

GEORGE HURFORD, OF LONDON, ENGLAND.

TOBACCO PIPE.

Application filed September 17, 1923. Serial No. 663,201.

To all whom it may concern:

Be it known that I, GEORGE HURFORD, of 5 Cannon Road, Southgate, London, N. 14, England, a subject of the King of Great Britain, have invented certain new and useful Improvements in or Relating to Tobacco Pipes, of which the following is a specification.

This invention has reference to tobacco 10 pipes, and more particularly to that form designed to prevent the smoker from receiving into his mouth quantities of fluid containing nicotine.

The primary object and the effect of the 15 invention is to produce an improved pipe of normal exterior form which will eliminate the objectionable feature of moisture, laden with nicotine, being drawn up into the mouth, and which will enable the smoker to 20 smoke without the inconvenience and ill-effects resulting therefrom.

Another object of the invention is to prevent the saliva from coming into contact 25 with the tobacco in the bowl of the pipe thus preventing the formation of nicotine, thereby allowing the smoker to consume all the tobacco which hitherto has been partly wasted through its having become damp.

In the pipe hereinafter described, the objects and effects above mentioned are accomplished, and while, for convenience, one embodiment only of the invention will be specifically described, it is to be understood that 30 it can be applied with but little modification to other forms.

The principle of the invention is that the saliva from the mouth is not permitted to mix with the nicotine from the heated tobacco but is directed to a point where it is 40 prevented from being drawn back again through the mouth piece and at the same time maintaining a direct channel for the passage of the smoke. This is effected by trapping the saliva and moisture into a chamber or sump located directly under the smoke chamber or passage.

In the preferred embodiment shown in Fig. 1 of the drawing, the pipe is so made 45 that whilst preserving its normal exterior form, the interior is provided with two chambers or passages, one directly over the other, and for simplicity of construction may be so drilled that the passages take the form of a figure 8 as shown in section Fig. 2, the upper and small passage 1 to provide for the withdrawing of the tobacco

smoke and the lower and larger passage 2 adapted for the moisture chamber. The nicotine and saliva from the smoke passage is drained to the moisture chamber 2 by 60 means of a slot 3 over the whole of the length of the intervening wall between the two passages. It will be appreciated that the provision of the chamber 2 permits cooling of the smoke before passing into the 65 mouthpiece.

The mouthpiece is of the usual shape but so drilled out of centre (indicated at 4, Fig. 1) to clear the moisture chamber 2, in 70 order to be in alignment with the smoke passage 1 and above the level of the moisture chamber. The smoke passage being of a larger diameter than the opening 4, in the mouthpiece an annular shoulder 5 is provided which further prevents the egress of 75 moisture to the mouthpiece.

The hole in the bowl leading to the smoke passage and the opening in the mouthpiece being in substantial alignment without angles or bends a free and easy passage of the 80 smoke is maintained. The opening 4 in the mouthpiece being above the level of the chamber 2, therefore once the moisture from the mouth has passed into the smoke passage, it drains into the moisture chamber 2 85 and cannot be drawn back into the mouthpiece after having mixed with the nicotine. Similarly, the hole in the bowl leading to the smoke passage is also above the level of the moisture chamber so that the moisture 90 cannot pass into the bowl after once having passed into the chamber 2.

A distinguishing mark or other means can be placed on the mouthpiece to indicate its 95 correct position.

The portion of the pipe containing the smoke passage and moisture chamber can be of the usual length but it is to be understood that the greater the length of the passages the more efficient the action. For 100 those who prefer the short chubby pipe necessitating shorter passages, satisfactory results are still obtained as called for in the present invention.

What I claim as my invention and desire 105 to secure by Letters Patent of the United States of America is:—

1. A tobacco pipe comprising a bowl, a stem, said stem being constructed with a pair of superposed passages formed wholly within the stem without external openings 110 and being interconnected throughout their

length by a slot, one end of the upper of said passages terminating in said bowl while the corresponding end of the lower said passage terminates within the stem, and a mouth-
5 piece serving as a single closure for the other ends of both said passages and having a bore in alignment with said upper passage.
2. A tobacco pipe comprising a bowl, a stem and a mouth piece all of normal and
10 symmetrical external contour and appearance, said stem being provided with a smoke

passage eccentrically formed therein and a second passage formed in said stem under said smoke passage and connected therewith throughout its length by a slot, said second 15 passage being without external openings, said mouthpiece forming a closure for said second passage and provided with an eccentric bore in alignment with said smoke passage.

In witness whereof I affix my signature.
GEORGE HURFORD.
